US0D1081885S

(12) **United States Design Patent** (10) **Patent No.:** **US D1,081,885 S**
(45) **Date of Patent:** **** Jul. 1, 2025**

(54) **DOMED GOLF BALL MARKER**

(71) Applicant: **On Point Ball Marker LLC**, Basalt, CO (US)

(72) Inventors: **Briston Peterson**, Basalt, CO (US); **James Joseph Verna**, Basalt, CO (US)

(73) Assignee: **On Point Ball Marker LLC**

(**) Term: **15 Years**

(21) Appl. No.: **29/893,183**

(22) Filed: **May 25, 2023**

Related U.S. Application Data

(60) Continuation of application No. 29/791,552, filed on Jan. 17, 2022, now Pat. No. Des. 995,680, which is a continuation of application No. 29/720,443, filed on Jan. 13, 2020, now Pat. No. Des. 943,042, which is a division of application No. 29/655,568, filed on Jul. 5, 2018, now Pat. No. Des. 872,817.

(57) **CLAIM**

The ornamental design for a domed golf ball marker as shown and described.

DESCRIPTION

FIG. 1 is a top perspective view of a domed golf ball marker in accordance with the new design;

FIG. 2 is an exploded bottom perspective view thereof;

FIG. 3 is a bottom plan view thereof;

FIG. 4 is a top plan view thereof;

FIG. 5 is a right-side elevational view thereof, with the left side elevational view being a mirror image to FIG. 5; and, FIG. 6 is a front elevational view thereof, with the rear elevational view being a mirror image to FIG. 6.

The broken lines in FIGS. 1-6 illustrate portions of the domed golf ball marker that form no part of the claimed design.

1 Claim, 5 Drawing Sheets
